(57) **CLAIM**

The ornamental design for a pet chew, as shown and described.

DESCRIPTION

FIG. 1 is a front perspective view of a first embodiment of a pet chew, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a front perspective view of a second embodiment of a pet chew, showing our new design;

FIG. 9 is a front elevation view thereof;

FIG. 10 is a rear elevation view thereof;

FIG. 11 is a left side elevation view thereof;

FIG. 12 is a right side elevation view thereof;

FIG. 13 is a top plan view thereof; and,

FIG. 14 is a bottom plan view thereof.

The break lines shown in the middle portion of the pet chew in FIGS. 1-3, 6-10 and 13-14 indicate that the appearance of any portion of the article between the break lines form no part of the claimed design.
